UNITED STATES PATENT OFFICE.

ELI C. FROST, OF ELMIRA, NEW YORK.

CANDY-FURNACE AND OVEN COMBINED.

SPECIFICATION forming part of Letters Patent No. 372,663, dated November 8, 1887.

Application filed October 13, 1884. Serial No. 145,536. (No model.)

To all whom it may concern:

Be it known that I, ELI C. FROST, a citizen of the United States, residing at Elmira, New York, have invented certain new and useful 5 Improvements in Candy-Furnaces and Ovens Combined, of which the following is a specification.

This invention has relation to improvements in a combined oven and candy-furnace; and 10 it consists in the construction and arrangement of parts, as will be hereinafter described, and particularly pointed out in the claim.

The object of my invention is to produce a 15 combined candy-furnace and baking-oven, whereby the fire from the furnace will be utilized to supply the oven with sufficient heat for baking or other purposes.

In the accompanying drawings, Figure 1 is 20 a sectional side elevation of my furnace and oven combined. Fig. 2 is a horizontal sectional view of my device.

The letter A represents what I term the 25 "candy-furnace," in which is placed the cast-iron fire-pot B, preferably in cylindrical form, which is provided with a grate, a, below which is the ash-pan b; and c is a door through which the ashes may be removed from said pan when occasion requires it. The furnace is practically 30 an extension of the oven D, and is preferably an integral part thereof, as clearly

shown in Fig. 2. An opening, d, in the top of the furnace is designed to receive the fuel, and over which is placed a vessel, in which the candy is made.

The letter E represents a drum arranged 35 within the oven, and F is a pipe connected to the fire-pot near the top of the furnace and preferably to one side thereof. This pipe extends from the furnace horizontally downwardly and rearwardly, and communicates 40 with the drum E of the oven. A pipe, F', communicates with the upper portion of the drum, and has its exit through the top of the oven. The oven is provided with a series of shelves, i, connected to the walls of said oven by means 45 of ribs or ways h. The oven is also provided with a door, H, whereby access is had to the interior thereof.

Having described my invention, what I 50 claim is—

The combination, with the furnace A, the oven D, and drum E, of a pipe, F, extending from the furnace horizontally downwardly and rearwardly and communicating with the drum, and a pipe, F', leading from the drum through 55 the top of the oven, as shown and described.

ELI C. FROST.
